UNITED STATES PATENT OFFICE.

BRYAN P. JOYCE, OF DAVENPORT, IOWA.

COUNTER-RECOIL-REGULATING MECHANISM.

Application filed May 7, 1923. Serial No. 637,243.

To all whom it may concern:

Be it known that I, BRYAN P. JOYCE, a citizen of the United States, and a resident of Davenport, county of Scott, and State of Iowa, have invented an Improvement in Counter-Recoil-Regulating Mechanism, of which the following is a specification.

The subject of this invention is a valve for regulating the speed of counter-recoil in 10 a recuperator mechanism.

The main object of the invention is the provision of means for automatically varying the time which it will take for fluid to pass from the recuperator cylinder into the 15 recoil cylinder, upon counter-recoil, to compensate for the position of elevation of the gun.

I attain the above object by a gravity actuated valve which varies the throttling 20 opening for return flow in accordance with the position of elevation of the gun.

With the foregoing and other objects in view, my invention resides in the novel arrangement and combination of parts and in 25 the details of construction hereinafter described and claimed, it being understood that changes in the precise embodiment of the invention herein disclosed may be made within the scope of what is claimed without 30 departing from the spirit of the invention.

A practical embodiment of the invention is shown in the accompanying drawing, wherein:

Fig. 1 is a fragmentary view in longitudinal section of a recuperator cylinder containing control mechanism constructed in accordance with my invention;

Fig. 2 is a sectional view taken on the line 2-2 of Fig. 1;

Fig. 3 is a sectional view taken on the line 3-3 of Fig. 1.

Referring to the drawing by numerals of reference:

A recuperator cylinder 10 is provided with 45 a port 11 through which fluid may flow from and to the recoil cylinder, not shown. Within the recuperator cylinder is mounted a housing 12 provided with a series of inlet ports 13 some of which ports are closed by 50 a valve 14 normally seated upon such ports and held upon its seat by a spring 15.

When the fluid, due to recoil of the gun, rushes from the recoil cylinder through port 11 into the recuperator cylinder it passes 55 through the ports 13 and elevates the valve 14 against the action of the spring 15, being

then free to pass through ports 16 into the throttling chamber 17.

When the recoil ends and counter-recoil starts, valve 14 is again seated thereby closing the ports 13, in which instance the returning fluid passes through duct 17 formed in the housing, and thence through a port 18 and the apertures 19 formed in a disc like valve 20, which is mounted for oscillation 60 within the casing on a pin 21 and which is automatically moved to different positions as the gun is elevated through gravity acting on a weight 22 formed at the end of an arm 23 which extends radially from the valve. 65 From the apertures 19 the fluid passes through a port 24 formed in the casing and thence through a port 11 to the recoil cylinder.

From the foregoing it will be seen that 75 as the gun is elevated more of the openings 19 are brought into register with the ports 18 and 24 thus permitting a greater volume of fluid to pass in a given time through said 80 ports and thus compensating for the extra weight to be returned to battery.

I claim:

1. The combination with a recuperator cylinder provided with a port, of a housing 85 within the cylinder provided with ports for the entrance of fluid and with a duct and ports for the exit of fluid, a valve for closing entrance ports against return flow and a gravity actuated valve mounted for oscillation in the housing provided with a series 90 of apertures one or more of which may register with the exit ports.

2. The combination with a recuperator cylinder provided with a port, of a housing 95 within the cylinder, provided with ports for the exit of fluid and a gravity actuated valve mounted for oscillation in the housing provided with a series of apertures one or more of which may register with the exit ports.

3. The combination with a recuperator cylinder provided with a port, of a housing 100 within the cylinder provided with ports for the entrance of fluid and with a duct and ports for the exit of fluid, a valve for closing the entrance ports against return flow 105 and means mounted in the housing for varying the amount of opening of the exit ports in proportion to the elevation of the gun.

4. The combination with a recuperator cylinder provided with a port, of a housing 110 within the cylinder provided with ports for the entrance of fluid and with a duct and

ports for the exit of the fluid, a valve for closing the entrance ports against return flow and gravity actuated means mounted in the housing for varying the amount of opening of the exit ports in proportion to the elevation of the gun.

5. The combination with a recuperator cylinder provided with a port, of a housing

within the cylinder provided with ports for the entrance of fluid and with ports for the exit of fluid, means for closing the entrance ports against return flow and automatic means mounted in the housing for varying the amount of opening of the exit ports in accordance with the elevation of the gun.

BRYAN P. JOYCE.
